UNITED STATES PATENT OFFICE

GEORGE H. MAGRATH, OF WHITINSVILLE, MASSACHUSETTS

BOBBIN CLUTCH

Application filed July 29, 1932. Serial No. 625,972.

This invention relates to bobbin clutches of the type having expansible clutching members which maintain the bobbin firmly in position during the spinning operation. Such devices are driven at very high speeds and are quite often subjected to vibrations and such severe usage that the spring member which holds the clutching members in expanded position either breaks or fails to function properly, and in either case it is necessary to dismember the device and either readjust or replace the spring. As such members as the case or sleeve and the cap for seating the bobbin have a pressed fit about the blade and whirl, it is practically impossible to dismember such a device without destroying those members. Furthermore, in order to vary the frictional engagement or grip of the clutching members, it is necessary either to readjust or replace the spring member, which likewise necessitates dismembering the device and providing a new cap and case. The cost of making such repairs and readjustments, as well as the time and resulting inconvenience, adds considerably to the expense of the spinning operation and in the course of a year amounts to an appreciable sum.

The principal object of this invention is to provide a bobbin clutch which is so constructed that the spring member may be easily and quickly replaced without dismembering the entire device or injuring or destroying any of the constituent parts.

Another object of the invention is to provide a bobbin clutch which is of simple and durable construction having but few parts, which is economical to manufacture and easy to assemble, and which is generally superior to those clutches heretofore used.

Further objects will be apparent from a consideration of the following description and the accompanying drawing which shows different embodiments of the invention chosen for the purpose of illustration.

In the drawing:

Fig. 1 is a side elevation, partly in vertical section, of a bobbin clutch embodying one form of the invention;

Fig. 2 is a section on the line 2—2 of Fig. 1;

Figs. 3 and 4 are plan and side views, respectively, of the cap member shown in Fig. 1;

Fig. 5 is a vertical section, similar to Fig. 1, showing a modified form of the invention;

Figs. 6 and 7 are respective plan and side views, with parts broken away, of the cap member shown in Fig. 5;

Fig. 8 is a fragmentary vertical section illustrating another modification; and

Fig. 9 is a view of an alternative form of spring member.

The bobbin clutch shown in Figs. 1 to 4 comprises a blade 1 having a whirl 2 rigidly secured thereto in the usual manner. The upper face of the whirl is provided with an annular concentric recess 3 surrounding the neck 4 and spaced inwardly from the shoulder 5. A cap 6, which is of rigid construction and having a cylindrical shape, has a pressed fit about the whirl with its upper face spaced from that of the whirl. As shown more clearly in Figs. 3 and 4, the cap is provided with a plurality of circumferentially spaced openings which extend radially thereof and communicate with the circumferential groove 8 on the outer face of the cap adjacent to its upper face 9 which provides an annular seat for the bobbin.

Mounted on the blade 1 and in spaced coaxial relation to the whirl is a case 12, which is of usual construction, having a plurality of symmetrically disposed downwardly extending spaced fingers 13 which project below the upper face 9 of the cap. The bobbin clutching members 14 are circumposed about the blade with their contact segments 15 disposed in the slots between the case fingers 13 and are fulcrumed about their lower ends, which are seated in the annular recess 3, as shown in Fig. 1. The lower ends of the clutch members are provided with laterally offset portions or arms 16 which project outwardly through the openings 7, while their upper ends are lipped and extend interiorly of the case 12 which limits the outward radial movement of the contact segments relative to the blade. An annular contractile

spring 18 is disposed in the circumferential groove 8 and being normally under tension yieldingly engages the end portions of the arm 16 thereby to hold the contact segments 5 in expanded position as shown in Fig. 1.

In this particular embodiment the circumferential groove 8 is provided with a beveled upper surface, as shown in Fig. 4, which causes the spring member 18 to act 10 downwardly at an angle upon the upper surface of the arm 16. The depth of the groove 8 is preferably such as to protect the spring member 18 against injury and also to prevent any danger of accidental displacement 15 thereof. It will be noted that this construction permits the quick removal and replacement of the spring member without dismembering or injuring any of the other elements, and without sacrificing any of the advantageous features characteristic of prior constructions. 20

In the embodiment shown in Figs. 5, 6 and 7, the construction of the blade, whirl and case are substantially identical to the corresponding members shown in Figs. 1 to 4, while the cap 6^a is somewhat similar, comprising a cylindrical body portion having circumferentially spaced radial openings 7^a which communicate with circumferential groove 8^a which is of semi-circular cross section. The clutching members 14^a, as in the previous embodiment, are fulcrumed about their ends to rock radially of the blade and are provided with laterally extending arms 35 16^a which project through the openings 7^a in the cap and terminate in downwardly directed feet 17. The coil spring 18 is disposed in the groove 8^a and yieldingly engages the feet 17 and normally holds the contact segments in expanded position. 40

In the construction shown in Fig. 8 the blade, cap and case are substantially the same as those shown in the previously described embodiment, but the annular recess 45 in the upper face of the whirl is dispensed with. The L-shape clutch members 24 are seated on the upper face of the whirl and are fulcrumed about the neck 4 with their lateral arms 25 projecting through the radial openings in the cap. Preferably the end portions of the arms 25 are grooved to receive the spring member 18, which normally holds the contact segments in expanded position. 50

55 In place of the coil or helical spring member 18 shown in Figs. 1, 5 and 8 a resilient split ring 30, as shown in Fig. 9, may be used. In either case the spring member may be easily drawn over the cap and accurately positioned in the circumferential groove, and may also be quickly removed without injury to the cap, case, or clutching members. 60

65 While I have shown and described certain desirable embodiments of the invention, it is to be understood that the present disclosure

is for the purpose of illustration only and that various changes in shape, proportion, and arrangement of parts, as well as the substitution of equivalent elements for those herein shown and described may be made 70 without departing from the spirit and scope of the invention as set forth in the appended claims.

I claim:

1. A bobbin clutch comprising a blade, a whirl secured to the blade, a cap fitting about the whirl, said cap having a plurality of spaced openings, bobbin contact means circumposed about said blade and fulcrumed to rock radially thereof, said contact means having offset portions projecting outwardly through the openings in said cap, and means circumposed about said cap for yieldingly engaging said offset portions to move said contact means outwardly from said blade. 75

2. A bobbin clutch comprising a blade, a whirl secured to the blade, a cap fitting about the whirl, said cap having a plurality of spaced openings, bobbin contact means circumposed about said blade and fulcrumed to rock radially thereof, said contact means having offset portions projecting outwardly through the openings in said cap, means for limiting the outward movement of said contact means, and means circumposed about said cap for yieldingly engaging said offset portions to move said contact means outwardly from said blade. 80

3. A bobbin clutch comprising a blade, a whirl secured to the blade, a cap fitting about the whirl, said cap having a plurality of spaced openings, a case mounted on the blade and having downwardly extending spaced fingers, bobbin contact means disposed in the spaces between said fingers and fulcrumed to rock radially of said blade, said contact means having laterally offset portions projecting outwardly through the openings in said cap, and an annular resilient member circumposed about said cap for yieldingly engaging said offset portions to move said contact means outwardly from said blade. 95

4. A bobbin clutch comprising a blade, a whirl secured to the blade, a cap fitting about the whirl, said cap having a plurality of spaced openings extending radially thereof and a circumferential groove on its outer face communicating with said opening, bobbin clutching members circumposed about said blade and fulcrumed to rock radially thereof, said contact members having laterally offset portions projecting outwardly through the openings in said cap, and an annular resilient member disposed in said groove and yieldingly engaging said offset portions to rock said clutching members outwardly from said blade. 100

5. A bobbin clutch comprising a blade, a whirl secured to said blade having an annular recess in its upper face concentric with the 110

- blade, a cap fitting about the whirl, said cap having a plurality of spaced openings extending radially thereof and a circumferential groove on its outer face communicating with 5 said openings, bobbin clutching members circumposed about said blade with the lower ends seated in said recess and providing fulcrum axes, said clutching members having laterally extending arms projecting outwardly through the openings in said cap, and an annular resilient member disposed in said groove and yieldingly engaging the outer ends of said arms to rock said clutching members outwardly in radial directions. 10
6. A bobbin clutch comprising a blade, a whirl secured to said blade having an annular recess in its upper face concentric with the blade, a case mounted on the blade and having downwardly extending spaced fingers, 15 a cap fitting about the whirl, said cap having a plurality of spaced openings extending radially thereof and a circumferential groove on its outer face communicating with said openings, bobbin clutching members disposed 20 in the spaces between said fingers with their lower ends disposed in said recess and their upper ends extending interiorly of the case, said members having laterally extending arms projecting outwardly through the openings in said cap, and an annular spring disposed 25 in said groove and yieldingly engaging the outer ends of said arms to rock said clutching members outwardly in radial directions. 30
7. A bobbin clutch comprising a blade, a whirl secured to said blade, a case mounted on the blade and having downwardly extending spaced fingers, a cap fitting about the whirl, said cap having a plurality of spaced 35 openings extending radially thereof, L-shaped clutching members having contact segments disposed in the spaces between said fingers and fulcrumed to rock radially of said blade, the lower ends of said members projecting outwardly through the openings in 40 said cap and their upper ends extending interiorly of the case, and an annular spring circumposed about said cap and yieldingly engaging the lower ends of said clutching 45 members to urge said contact segments outwardly from the blade. 50
8. A bobbin clutch comprising a blade, a whirl member on the blade, bobbin contact means disposed about the blade to rock radially 55 thereof and having offset portions projecting outwardly adjacent the upper end of the whirl member, a cap member having a portion overlying said offset portions, one of said members having peripheral openings, and 60 spring means acting upon said offset portions through said openings yieldingly to rock said contact means against the bobbin. 65
9. A bobbin clutch comprising a blade, a whirl member on the blade, bobbin contact means disposed about the blade to rock radial- 70 ly thereof and having offset portions projecting outwardly adjacent the upper end of the whirl member, a cap member mounted on the whirl member with a portion overlying said offset portions, one of said members having peripheral openings, and spring means acting upon said offset portions through said openings yieldingly to rock said contact means against the bobbin. 75
